UNITED STATES PATENT OFFICE.

ALBERT HENRY MIDGLEY, OF ACTON VALE, ENGLAND, ASSIGNOR OF ONE-HALF TO
CHARLES ANTHONY VANDERVELL, OF ACTON VALE, ENGLAND.

TIME-FUSE FOR SHELLS.

1,301,479.

Specification of Letters Patent. Patented Apr. 22, 1919.

Application filed May 23, 1917. Serial No. 170,542.

To all whom it may concern:

Be it known that I, ALBERT HENRY MIDGLEY, a subject of the King of Great Britain and Ireland, and residing at Warple Way, Acton Vale, in the county of Middlesex, England, have invented certain new and useful Improvements in and Relating to Time-Fuses for Shells, of which the following is a specification.

10 This invention relates to time fuses for shells of the kind in which the timing is effected by punching a lead or like covered fuse at a point more or less distant from its point of connection with the space communicating with the primer, according to the time it is desired to lapse between the moment of firing and that of explosion.

It is known to place the fuse composition of a time fuse in two adjacent grooves and 20 to separate the two adjacent portions of the fuse from each other, with the exception of a small passage which can be shifted between the two adjacent portions for the purpose of timing the fuse.

25 The present invention consists in the combination of a lead or like covered fuse arranged in the manner just referred to, with a movable member provided with a hole arranged to register with the passage between 30 the two adjacent portions of the fuse in such a manner as to be able to introduce a punch for the purpose of laterally punching the fuse.

The invention also consists in the use of 35 a lead or like covered fuse bent back on itself in the form of a hairpin so as to form the two adjacent portions above referred to which are separated from each other by a movable incomplete ring arranged to be 40 moved together with the movable member provided with the punching hole.

The invention also consists in the improved construction of a time fuse as hereinafter more particularly referred to.

45 Referring to the accompanying drawings which illustrate the invention by way of example:—

Figure 1 is a sectional elevation along the line I I of Fig 2.

50 Fig. 2 is a sectional plan along the line AB of Fig. 1, and

Fig. 3 is an elevation of the improved time fuse.

Referring to the drawings, the fuse holder 55 a is provided on its cylindrical periphery

with an annular recess b or with a portion of such recess, adapted to receive a lead covered or similar fuse c bent back on itself in the form of a hairpin, the two ends c¹ c² of the fuse being inserted into substantially 60 radial holes leading to the spaces d¹ d² communicating with the primer and the explosive respectively, and its two adjacent portions which lie in the annular recess being separated from each other by an incomplete bipartite flat ring e fitting in a groove provided in the bottom of the recess. The recess b, the radial depth of which at and in the proximity of the bend c³ of the fuse is made greater than in the remaining portion 65 thereof for the purpose of being able to bend the fuse back on itself without interfering with the continuity of the ring, is covered by a sleeve f which is adapted to be rotated on the fuse holder a and to carry 70 with it the separating ring e, for instance through the intermediary of a spring g secured to the sleeve f and carrying pins g¹, arranged to slide in holes f¹ provided in the sleeve f and to engage in notches e¹ provided 75 in the separating ring e. At the point opposite the incomplete portion e² of the separating ring e, the sleeve f is provided with a hole f² of the required dimension to permit of a punch being inserted therein for 80 the purpose of laterally punching the two adjacent portions of the fuse.

The rotary sleeve f and the fixed fuse holder a are provided with an index f³ and with graduations h respectively for the purpose of indicating the timing of the fuse which is determined by the position of the sleeve relatively to the holder. The recess in which the fuse is mounted is preferably 85 beveled as shown at b¹ and the portions of the rotary sleeve facing the beveled portions of the recess are preferably provided with holes f⁴ to allow the gases to escape.

The end c² of the fuse preferably terminates into a ring i for the purpose of directing the flame downward through the hole i¹ of the ring.

The operation of the fuse hereinbefore described is as follows:—

The rotary sleeve f is turned on the fixed 105 holder a until the index f³ thereon comes to lie in front of the graduation corresponding to the required timing. While the sleeve is thus rotated it carries with it the separating ring e between the two adjacent por- 110

- tions of the fuse *c*, whereby the position of the punching hole *f*² provided in the sleeve *f* and of the incomplete portion *e*² of the separating ring *e* is altered relatively to the two ends *c*¹, *c*² of the fuse, with the consequence that the operative length of the fuse, extending from the space *d*¹ communicating with the primer to the incomplete portion *e*² of the separating ring *e*, and across this passage (provided the fuse has been punched at this point) and through the adjacent portion of the fuse lying underneath to the space *d*² communicating with the explosive in the shell, is also altered.
- It will thus be seen that in the event of the fuse having been punched in a wrong position, the same can always be punched again in another position and be efficiently used in spite of the previous punching, since the only means of communication between the two separate compartments containing the adjacent portions of the fuse is the incomplete portion *e*² of the separating ring *e*, so that when the latter is moved around until the incomplete portion comes to lie in the position corresponding to the proper timing, the portions previously wrongly punched are now separated from each other by the interposing ring *e*.
- It will also be seen that if the lead covered fuse has not been effectively punched, the same will still be operative, although the time will not be correct, since in this case the burning of the fuse will continue along the two complete adjacent portions of the fuse between its two ends.

I wish it to be understood that the invention hereinbefore described is not limited to the mode of carrying it into effect above referred to and that the details of construction may be varied without in any way departing from the spirit of the invention. For instance, instead of arranging the fuse in a recess provided in the cylindrical periphery of the fuse holder the same may be arranged in a groove formed in the upper surface thereof, the rotary sleeve being in this case replaced by a rotary ring.

What I claim is:

1. A time fuse for shells having a fuse holder, a covered fuse mounted thereon and having two adjacent parts, a separating movable member arranged between the adjacent parts of the fuse, an opening provided in said separating movable member, a movable member for covering the adjacent parts of the fuse, and a punching hole provided in the latter movable member and arranged to register with the opening in the separating movable member, as set forth.
2. A time fuse for shells having a fuse holder, a covered fuse mounted thereon, said

fuse being bent back on itself in the form of a hairpin so as to have two adjacent parts, a separating movable member arranged between the adjacent parts of the fuse, an opening provided in said separating movable member, a movable member for covering the adjacent parts of the fuse and a punching hole provided in the latter movable member and arranged to register with the opening in the separating movable member, as set forth. 65

3. A time fuse for shells having a fuse holder, a covered fuse mounted thereon and having two adjacent parts, a movable ring arranged between said adjacent parts of the fuse and formed with a gap, a movable member for covering the adjacent parts of the fuse, and a punching hole in the latter movable member arranged to register with the gap in the ring, as and for the purpose set forth. 75

4. A time fuse for shells having a fuse holder, a recess formed on the cylindrical periphery of the fuse holder, a covered fuse mounted in said recess and having two adjacent parts, a separating movable member arranged in said recess between the adjacent parts of the fuse, an opening in said separating movable member, a movable sleeve for covering the said recess and adjacent parts of the fuse mounted therein, and a punching hole in said sleeve arranged to register with the opening in the separating movable member, as and for the purpose set forth. 90 95

5. A time fuse for shells having a fuse holder, a recess formed on the periphery of the fuse holder, a covered fuse mounted in said recess and bent back on itself in the form of a hairpin so as to have adjacent parts, the radial depth of the recess receiving the fuse being made greater in the proximity of the bend of the fuse, a movable member for covering the recess and the adjacent parts of the fuse, and a punching hole 100 in said movable member for punching the adjacent parts of the fuse laterally, as set forth. 105

6. A time fuse for shells having a fuse holder, an annular recess provided on the 110 periphery of the fuse holder, a covered fuse mounted in the said recess and having adjacent parts, a separating ring provided between the adjacent parts of the fuse and having a gap, a rotary sleeve for covering the said recess and the adjacent parts of the fuse, a punching hole in the said rotary sleeve arranged to register with the gap in the separating ring and means for connecting together the rotary sleeve and the ring, 115 as and for the purpose set forth. 120

In testimony whereof I have signed my name to this specification.

ALBERT HENRY MIDGLEY.
